(57) **CLAIM**

We claim the ornamental design for a control panel for drum washing machine, as shown and described.

DESCRIPTION

FIG. 1 is a front, right, top perspective view of a control panel for drum washing machine showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a front, right, top perspective view thereof shown as part of a drum washing machine.

The broken line showing of an appliance in FIG. 8 is included for the purpose of illustrating environment of the control panel for drum washing machine and forms no part of the claimed design.
